METHOD OF DISINTEGRATION, DISPER-
SION, STABILIZATION, AND COLLECTION
OF SOLID MATERIALS

Lewis M. McBride, Corozal, C. Z.

Application August 12, 1935, Serial No. 35,720

6 Claims. (Cl. 83—94)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to the disintegration of solid substances, the dispersion thereof after disintegration, a means of stabilizing the fine particles of disintegrated and dispersed material to prevent recombining and a means of collecting 10 the disintegrated, dispersed and stabilized substance or substances.

One of the objects of this invention is to provide a method of producing a fine dust-like material that will retain its characteristics without 15 recombining into larger particles.

Another object is to provide a means of intensifying, increasing or enabling the capacity or ability of fine dust particles to adsorb upon themselves a film of air or other gas.

20 Another object is to provide a means to facilitate and augment the natural tendency of fine dust particles to acquire a definite electrical charge.

Another object is to provide a means of producing 25 a substance consisting of one material as an active component and another material as an inert component, disintegrated simultaneously and intimately associated together, whereby the particles of inert material tend to assist 30 in preventing the recombining or cohering of the active particles, the whole consisting of stabilized particles of active material with attached or adsorbed particles of inert material.

Another object is to provide a means of producing 35 a finely divided solid material consisting of two or more components of active material in a stabilized condition, such that the individual particles of one component will not recombine or cohere with other particles of the same component and, also, such that the particles of different components will not combine with or adhere to each other.

In all processes of mechanical disintegration, 40 the different particles into which the substance is divided have to be torn apart against the force of cohesion. Disintegration may be accomplished by shearing and tensile stresses gradually applied, as in attrition mills, or by a crushing pressure applied gradually by means of rolls, 45 or by sudden blows, as in impact machines of the disintegrator type.

The efficiency with which the applied stress can act will depend upon the rigidity with which it is received by the pieces of substance that are to be broken. As the particles gradually be-

come smaller, they form a loose dust that yields more and more to the applied stress, so that the crushing effect is increasingly diminished. There comes a point, therefore, in all crushing operations at which the accumulated débris is fine enough to accommodate itself to the applied stress without the individual particles actually being stressed beyond their elastic limit. The rigidity of the mass is then too low for further crushing stresses to produce any effect. 10

To disintegrate the material further, it is evident that the finest particles of the débris which are cushioning the larger remaining particles against the crushing effect of the process must be removed in order to allow the disintegration 15 action to continue. To separate these finest particles from the coarse and remove them from the crushing process and continue the disintegration of the remainder is one of the principal features of this invention. 20

The manner in which this is done contributes directly to another principal feature of the invention by disassociating any aggregates and dispersing the fine particles and isolating them in air or other gas whereby they are permitted and 25 caused to adsorb upon their surfaces molecules or films of air or gas; also, by virtue of the process, fine particles of a particular type of material, according to its chemical nature, acquire an electrical charge of a definite sign, the 30 adsorbed air or gas and/or the effect of the electrical charges produce a stabilized particle preventing recombining or the formation of aggregates of the individual particles. Further, the method used to accomplish these results is 35 also used to provide a convenient means of retaining and collecting the processed material for use.

The combination of the successive processes of disintegration, separation, dispersion, stabilization and collection constitute the basis of this 40 invention and is accomplished by the methods and apparatus as follows.

In the drawings:

Fig. 1 is a sectionalized side elevation of the 45 disintegration mill.

Fig. 2 is an end view of Fig. 1 with end parts removed.

Fig. 3 is a side elevation of the assembly of 50 the various apparatus of the system.

In Fig. 1 is shown the barrel or steel cylinder 1, having heads 2, 2' provided with bearings 3, 3', rotatably mounted upon a stationary hollow shaft 4 clamped in the supports 5, 5', the hollow shaft being closed by the plug 6 and

provided with short upright pipes 7 and 7' threaded into the shaft and opening into the hollow cylinder on either side of the plug 6 and preferably near the interior ends of the cylinder. Plug 6 is held in place by a set screw 6'.

Enclosed within the barrel 1 are a number of steel rollers 8 arranged to roll freely on the lower interior circumference of the cylinder wall.

Fig. 2 is an end elevation of Fig. 1 with the 10 head 2 and the support 5 removed for clearness. The barrel 1 is provided with openings A, B and C spaced 120 degrees apart around the circumference and equidistant longitudinally, the middle opening B being preferably at about the center of the cylinder and opening A being toward the rear head 2' and leading opening B (by 120°) when the direction of rotation of the cylinder is as shown by the arrow or counter-clockwise as shown in Fig. 2, while opening C is toward the 15 front head 2 and following opening B by 120°. These openings may be closed or opened by means of plugs as shown at B Fig. 1.

In Fig. 3 is shown a side elevation of the assembly of the disintegrating, dispersing, separating and collecting system in which 1 is the mill of Figures 1 and 2, 10 is a motor or other means of rotatably driving the mill, 11 is a vacuum exhaust fan driven by the motor 11a or other suitable means, the suction side of the fan being 25 connected to the open end of the hollow shaft 4 outside of the support 5 and arranged to discharge into the centrifugal separator 12 through the pipe 13, the centrifugal separator being provided with a removably mounted collecting receptacle 12a at its lower end and an outlet at 30 12b communicating with the top of the dust settling and collecting chamber 14 through the pipe 15, the dust chamber 14 having a removably mounted collecting receptacle 14a at its lower end. The walls of the dust chamber 14 consist of one 35 or more layers of a suitable fabric filter which will permit the escape of the discharged and spent air or gas but which retains the fine dust particles, the area of the walls being proportioned to the volume of air or gas delivered by the vacuum exhaust fan 11, so that the velocity of air or gas through the filter will be relatively low.

With reference to Figures 1 and 2, a predetermined charge of material to be disintegrated 40 is placed within the cylinder 1 through one of the openings as at B, and initially the openings A, B and C are closed with plugs, the charge being represented at 16. Upon rotation of the cylinder 1 upon the stationary hollow shaft 4, the rollers 45 8, roll over the material 16 crushing and breaking it down to a certain extent; some of the material 16 is carried around with and over the rollers, which, rising on the side of rotation, are carried up by friction with the inside of the cylinder 1 of the mill until they are overbalanced 50 above the axis of the cylinder and fall back upon the top of following rollers as shown by the line of arrows, giving several impacts upon the top of succeeding rollers, further crushing the material 16 by impact. Continuous rotation of the cylinder 1 produces a continuous falling and impacting of the rollers 8. However, a point is soon reached where the accumulated fine material acts as a cushion, as hereinbefore explained, and this 55 condition is overcome as follows: First, with the end 4a of the hollow shaft 4 open, the vacuum exhauster is started and draws air through 4a, and the pipe 7' and across through the top of the interior of the cylinder and out through pipe 75 7, removing the fine dust carried into the air by

the continuing action of the cylinder and rollers.

This, however, removes only a portion of the extremely fine dust and to complete the process, the cylinder is stopped and with the vacuum exhauster still operating, one or all of the plugs 5 A, B and C are removed and the rotation of the cylinder again started. (The opening 4a may or may not be closed depending upon the extent of vacuum produced by the exhauster.)

The vacuum exhauster now draws air in 10 through the openings A, B and C, preventing any of the material from falling out, and removes the fine material from under and between the rollers carrying it through the pipe 7 allowing only the comparatively coarse uncrushed material to remain, upon which the action of the disintegrating process continues unobstructed.

The uniform angular spacing of the openings and the manner in which they lead one another successively from rear to front tends to agitate 20 the material under and between the entire surface of the rollers and to carry the fines from the rear to the front and out of the pipe 7. The constant and continuous removal of the fine particles permits the disintegrating action of the 25 mill to reduce the last remaining material to the finest proportions.

Referring to Fig. 3, the vacuum exhauster 11 is 30 preferably a multibladed high speed type, and serves a triple purpose; first, for producing a partial vacuum through the mill and removing the fine particles as described; second, to break up any aggregates of fine particles and to agitate and isolate individual particles in the air stream; and, third, to maintain the particles in the air 35 stream for a definite period of time by discharging through a considerable length of pipe 13 into a centrifugal separator 12 specially proportioned with reference to the fine nature of the material handled. Although this separator is similar 40 to a standard type of centrifuging collector as used commercially for various purposes it is used in this process as a separator rather than a collector in that the direction of the stream of high velocity, dust laden air being suddenly diverted causes any aggregation of fine particles, 45 that may have escaped separation previously in the process, to be torn apart and isolated.

The receptacle 12a is arranged for the collection and removal of such material as gravitates 50 to it, while at 12b is a central opening from the separator connected to the pipe 15 which carries the dust laden air to the collector 14, allowing the dust to be filtered out of the air by the walls of filter fabric 14, the finely divided and 55 stabilized particles being finally collected in the removable receptacle 14a as an impalpable powder which will not cake or form aggregates.

In some instances it has been found advantageous to mix an inert agent with the material to 60 be disintegrated and stabilized. Preferably the inert agent and the material are mixed prior to disintegration and then are fed into the mill. The fine particles are thus thoroughly mixed and are carried forward in the gaseous medium. Although the invention is not limited to this theory, I believe that the inert particles collect 65 around the surface of each particle of the active material, thus positively separating the particles of active material.

In the preparation of stabilized tear gas, the chloracetophenone has been mixed with such stabilizers as fuller's earth, chalk, magnesium oxide (calcined) or zinc oxide. I have found that not over 5% by weight of these stabilizing mate- 70 75

rials effectively prevents cohesion, coalescence or recombining of the tear gas when collected in bulk after treatment in accordance with this invention.

5 Reference has been made herein to the use of a gas other than air for dispersing and stabilizing the fine particles. This is accomplished by attaching a suitable connection, preferably a manifold or expansion chamber to the inlet end 10 4a of the hollow shaft 4, into which is released under pressure a gas of any desired kind or type, preferably by means of the usual commercial form of compressed gas cylinders.

The openings A, B and C in the barrel 1 are, in 15 this case, closed and the gas passed directly through the pipe 1', the interior of the cylinder 1 and out of the pipe 1 and to the vacuum ex- hauster 11, the operation of which is continued to agitate and separate the particles as herein- 20 before explained.

In the event that it is desired to mix an amount 25 of air with any particular kind of gas used, one or more of the plugged openings A, B and C may be opened to the atmosphere and the gas pressure so regulated that the vacuum exhauster will main- 30 tain a partial vacuum within the barrel 1.

Carbon dioxide or nitrogen may be used as the 35 stabilizing gas. If it is desired that no air be admitted, the rotating drum may be placed in a chamber to which the gas is admitted, whereby 40 openings A, B and C will draw gas only through the material. However, as above indicated, air may be drawn through the openings A, B and C and gas through the hollow shaft, the propor- 45 tions being easily varied by varying the gas pres- sure.

Although not shown in the drawings, ports 50 may be drilled in the hollow shaft 4 under the bearing of the head 2' and communicating with 40 radial ports drilled in the head 2' which in turn communicate with longitudinal ports drilled in the wall of the barrel 1 and these in turn opening into the interior of the barrel at points similar to the spacing and location of the openings 45 A, B and C, as described, and for the purpose of passing the compressed gas under and between the rollers 8, for the purpose and in a manner similar to that hereinbefore described.

Although this invention is not limited to any 55 specific material, it has been found especially useful in disintegrating, stabilizing and collecting normally solid materials used as disabling and incapacitating agents such as chloracetophenone and diphenylamine chlorarsine. Chloracetopheno- 60 ne, commonly called tear gas, is normally a solid and has heretofore been dispersed by dissolving it in an inert liquid, or by mixing it with powder and slowly burning the powder, or by an explosive charge.

65 Diphenylamine chlorarsine is also normally a solid which will decompose at a relatively low temperature, so that dispersion by a burning mu- nition results in loss of the diphenylamine chlorarsine. Some loss by decomposition also occurs when diphenylamine chlorarsine is dispersed by explosion due to the high temperature.

Chloracetophenone and diphenylamine chlor- 70 arsine disintegrated and stabilized in accordance with this invention may be dispersed directly as very fine dust, since these materials may be loaded in various munitions and containers and will not cake or recombine.

Furthermore, two or more of these or similar 75 materials may be disintegrated and mixed for use together. For example, chloracetophenone

and diphenylamine chlorarsine may be disintegrated separately in my mill and then mixed in proper proportions, or the mixture may be made prior to disintegration. Such a mixture will not cake and may be stored and dispersed in any 5 suitable manner such as by air pressure or from airplane spray or dusting apparatus. Also by means of artillery or mortar shell, bombs, grenades and other projectiles, static containers or land mines and other devices all of which may be 10 loaded with a bursting charge only sufficient to rupture the body of the projectile or other container and disperse its contents.

Although certain specific materials have been 15 mentioned herein which may be disintegrated, stabilized and collected by this method and apparatus, it is to be understood that there are many other material used in the various industries, sciences and arts, either separately or compounded, mixed or otherwise embodied in or with 20 other materials, that may be advantageously prepared as a finely divided and stabilized material by this method. A few of such instances are appended by way of illustration, as follows: medi- 25 cines, foods, fuels, ceramics, cements, cosmetics, paints, lubricants, abrasives, insecticides, disinfectants, paper, pencils, polishes, powder, rubber and other materials.

It is also to be understood that the apparatus 30 of this invention has been described and shown in its simplest form for the purpose of illustration, however, it is apparent that modifications and refinements may be made, without departing 35 from the principles involved, such, for example, as providing a means of feeding the ma- 40 terial, which is to be disintegrated, into the re- volving cylinder of the mill, and for opening and closing the various nlets of the apparatus without stopping the mill, thereby providing for continuous operation instead of intermittent op- 45 eration as described herein.

In the following claims the term "gaseous medium" is intended to include air or gas or a mixture of air and gas.

While I have shown and described the pre- 45 ferred embodiment of this invention, I wish it to be understood that I do not confine myself to the precise details herein set forth by way of illustration, as it will be apparent that many changes and variations may be made therein 50 by those skilled in the art without departing from the invention nor exceeding the scope of the appended claims.

I claim:

1. The method of disintegrating and stabilizing 55 normally solid irritant chemical agents material which normally cakes during storage, which comprises disintegrating the material and a mag- nesium oxide to fine dust particles continuously extracting only the finest dust particles, suspend- 60 ing and transporting the extracted dust particles of the materials in a moving stream of air, and collecting the fine dust particles thus stabilized.

2. The method of disintegrating and stabilizing 65 chloracetophenone to form a fine dust which will not cake during storage which comprises disintegrating the chloracetophenone to fine dust particles continuously extracting only the finest dust particles, suspending the extracted dust particles in air, and collecting the fine par- 70 ticles thus stabilized.

3. The method of preparing chloracetophenone 75 and diphenylamine chlorarsine in stabilized powder form for use as an offensive chemical agent which comprises simultaneously disintegrating

chloracetophenone and diphenylamine chlorarsine together to fine dust particles, intimately mixed, continuously extracting only the finest dust particles, suspending the mixed dust particles in air until they are stabilized, and collecting the mixed fine particles.

4. The method of disintegrating and stabilizing chloracetophenone and/or diphenylaminechlorarsine into fine dust particles which will not cake together during storage by the use of a rotary disintegrating impact mill, which comprises disintegrating the chloracetophenone and/or diphenylaminechlorarsine to fine dust, continuously withdrawing the very finely ground particles from an area spaced a substantial distance above the disintegrating area, and away from the turbulence of such area whereby only the finest floating particles are withdrawn, keeping said

particles suspended in a gaseous medium until each particle is surrounded by attached molecules of the gaseous medium, and collecting the stabilized particles.

5. The invention as defined in claim 4, the additional step of withdrawing the finely ground particles by a current of gaseous medium which in part passes through the chloracetophenone and/or diphenylamine chlorarsine being disintegrated.

6. The invention as defined in claim 4, the additional step of abruptly changing the direction of movement of the finely ground particles while in the gaseous medium to thereby separate any aggregates and insure intimate contact with the molecules of the gaseous medium.

LEWIS M. McBRIDE.
